UNITED STATES PATENT OFFICE

2,448,302

TOY HIGHWAY TRAFFIC SIGNAL LIGHT

Leslie L. Eyerkuss, Belleville, N. J.

Application February 21, 1947, Serial No. 730,103

7 Claims. (Cl. 177—329)

1

The invention relates particularly to highway traffic signal lights for toy electric railroads.

In such toy signal lights, the housing for the signal lamps is so small that difficulty has been experienced in inserting such lamps in their sockets and in removing same when necessary. Difficulty has also been experienced in mounting and positioning the colored elements, such as strips of transparencies, to provide the differently colored windows.

A prime object of the present invention is to demonstrate to a child the modern arrangement of traffic control at crossing points on the highway or railroad by means of differently colored light signals in such a manner that the child can control the traffic at will.

Another object is to facilitate the installation and removal of the lamps.

A further object is to provide improved means for mounting and positioning the colored elements for providing the differently colored windows.

Yet another object is to provide novel means for partitioning the lamp housing into separate compartments for receiving the lamps.

Still another object is to provide a signal light of this character that is simple in construction, inexpensive to manufacture and highly efficient in use.

Other objects and advantages of the invention will be apparent from the description thereof to follow taken in connection with the accompanying drawings in which—

Figure 1 is a side elevational view of a signal light embodying my invention, parts being shown in section.

Figure 2 is an enlarged vertical sectional view of the housing for the lamps.

Figure 3 is a similar view taken on a plane at right angles to the plane of Figure 2.

Figure 4 is an enlarged cross sectional view taken on the plane of the line 4—4 of Figure 1.

Figure 5 is a fragmentary side view of the lamp housing, with parts omitted and parts shown detached.

Figure 6 is a perspective view of a partition wall for the lamp housing.

Figure 7 is a perspective view of the rear wall of the lamp housing with lamps and partition walls mounted thereon.

Figure 8 is a cross-sectional view taken on the plane of the line 8—8 of Figure 1.

Figure 9 is a perspective view of the assembled colored elements for the lamp housing windows.

Figure 10 is a front view of a colored element.

2

Figure 11 is an edge view thereof.

Figure 12 is a diagrammatic view showing the lamp circuits.

Referring to the drawings, a sectional tubular metal post 1 is supported on an insulating base 2. Near the top, the post is provided with a laterally extending metal arm 3. A wire 4 has one end secured to the top of the post by means of a rivet 5 and its other end secured to the outer end 10 of the arm.

The lamp housing 6 is suspended from the outer end of the arm by means of a ring 7. This housing is formed of sheet metal having a front wall 8, side walls 9 and a rear wall 10 and is square in cross-section. The front wall 8 at its top and bottom ends extends rearwardly to provide top and bottom walls 11 and 12, respectively. The front and side walls are formed with aligned spaced windows 13, and the side edges of said walls are suitably secured together by soldering or the like.

The rear wall 10 is removable and is formed with an inwardly extending marginal flange 14, which flange frictionally fits over the inner free edges of the front and side walls. Spaced openings 15 are formed in the rear wall in alignment with the windows in the front and side walls.

The interior of the housing is divided by partition walls 16 into an upper compartment 17, a lower compartment 18 and an intermediate compartment 19. Each partition wall consists of a plate with a flange 20 along one edge thereof which is positioned behind and interlocked with an instruck portion 21 formed on the rear wall 10.

The windows 13 in the front and side walls are covered by strips 22 of transparent material such as Lumarith. Each strip is substantially the length of the housing and is suitably colored in different colors, such as red at one end as indicated at 23, green at the other end as indicated at 24 and yellow or amber in between as indicated at 25. These strips are positioned on the inner surfaces of the front and side walls across the windows and are secured therein by clamping same between the free edges of the partition walls 16 and the inner surfaces of the front and side walls. The strips are so arranged that in the side windows of the upper and lower compartments the colors are the same, with a different color in the front windows of said compartments, but the colors are displaced in the lower compartment as compared with the upper one.

For example, by reference to Figures 1 and 9, it will be seen that the two opposite side windows in the upper compartment are red and the front

window green. The two opposite side windows in the lower compartment are green and the front window red. The windows in the intermediate compartment are yellow, indicating caution.

A hood or shield member 26 is provided above each window 13 in the front and side walls. The hood member comprises an upper wall 27 and integral side walls 28. The inner edge of the upper wall is bent upwardly to form a flange 29 and the lower inner edge of each side wall 28 is formed with a protuberance 30. The hood member is mounted on the outside of the wall with its flange 27 fitted behind and in interlocking relation with an out-struck portion 31 formed on the wall just above the window, and with its protuberances 30 inserted in holes 32 in the wall below the window.

Miniature lamp sockets 33 are mounted in the openings 15 in the rear wall 10 and extend rearwardly of the wall. The sockets threaded receive lamps 34 which extend forwardly of the wall into the compartments of the housing. The lamps are energized through a step-down transformer 35, the primary of which is connected to an ordinary household lighting system. A suitable change over switch is positioned remotely from the signal light for switching over the lights from one direction of control to the other. The switch comprises an insulating base 36 having a terminal 37 and three spaced stationary contacts 38, 39 and 40, and a movable contact 41 adapted to be moved into contact with either of said contacts 38, 39 or 40 by a knob 42. Conductors 43, 44 and 45 connect the stationary contacts 38, 39 and 40, respectively, with binding posts 46, 47 and 48, respectively, on the insulating base 2. Leads 49, 50 and 51 passing upwardly through the post 1 and out through an eyeletted opening 52 in said post connect the insulated central terminals 53 of the lamps 34 in the upper compartment 17, intermediate compartment 19 and lower compartment 18, respectively, with the binding posts 46, 47 and 48, respectively. It will be understood that the threaded shells of the sockets 33 are connected to the metal rear wall 10 of the housing and grounded, thus grounding the other terminals of the lamps. Current is supplied to one end of the movable switch contact 41 from the transformer 35 through a lead 54 which is provided with a plug 55, and said current is conducted by said movable switch contact 41 to either of the stationary contacts 38, 39 or 40 according to the position of the movable contact.

In using the signal light, the housing 6 is positioned alongside the track of the toy railroad with its arm 3 over the railroad crossing or intersection of highways so that when danger is indicated for one track or highway clear is indicated for the other track or highway.

Referring to Figure 1, the movable switch contact 41 is shown in contact with the center stationary contact 39, closing the circuit through the lamp in the intermediate compartment 19 for indicating caution in both directions. The current passes through conductors 44 and 50 to the central terminal 53 of the lamp 34 in said compartment, and through said lamp to the shell of socket 33 which is grounded.

When the movable switch contact 41 is moved by the knob 42 to the stationary contact 40 at the right of the switch base 36, current passes through conductors 45 and 49 to the central terminal 53 of the lamp in the upper compartment 17 and through its socket causing the red win-

dows along the track or highway facing the sides of the housing, and the green window along the track or highway facing the front of the housing to light up; and vice versa when the movable switch contact 41 is moved into engagement with the stationary contact 38 at the left of the switch base 36, current passes through conductors 43 and 51 to the central terminal 53 of the lamp in the lower compartment 18 and through its socket causing the green windows along the track or highway facing the sides of the housing and the red windows along the track or highway facing the front of the housing to light up.

In assembling the housing, the shields 26 are easily inserted into position adjacent the windows. When the side and front walls are suitably secured together the strips 22 of colored material may be readily inserted in place against the inner surfaces of such walls. The partition walls 16 and lamps 34 form a unit with the rear wall 10 and this unit can easily be mounted on the housing by inserting the partition walls and lamps from the rear and sliding the marginal flange 14 of the rear wall over the rear edges of the front and side walls whereby the free edges of the partition walls will clamp the colored strips 22 against the front and side walls. Whenever necessary to give attention to the lamps or colored strips, the rear wall 10 can readily be removed by forcing the marginal flange 14 off of its seat whereby the wall and the lamps and partitions carried thereby will be accessible.

The improved signal light is simple and inexpensive to manufacture and operate and may be used with all types of electrically operated toy railroads.

What I claim is:

1. In a traffic signal for toy electric railroads, a lamp housing having fixed front and side walls and a removable rear wall, windows in said front and side walls, lamp sockets carried by said rear wall, transverse plates carried by said rear wall for partitioning the housing into compartments, and colored transparent strips extending across said windows and clamped between the edges of said transverse plates and the inner surfaces of said front and side walls.

2. A toy electrical signal comprising a housing having a plurality of compartments each having an opening therein, and a strip of transparent material overlying all of said openings and having a differently colored portion for each opening.

3. A toy electrical traffic signal including a lamp housing having fixed front and two oppositely disposed side walls and a rear wall, transverse plates carried by said rear wall for partitioning the housing into compartments, each compartment having a window in each of its front and side walls, an electric lamp in each of said compartments, a colored transparent strip for each of said walls extending across all of said openings therein, the strip for each side wall having green, yellow and red portions for the openings in said wall respectively in opposed relation to the green, yellow and red portions respectively of the strip for the opposite wall, and the strip for the openings in said front wall having red, yellow and green portions corresponding respectively to said green, yellow and red portions of said strip for the side walls.

4. The toy electrical traffic signal as defined in claim 3, wherein said rear wall is removable and has fixedly mounted thereon a lamp socket for each of said electric lamps.

5. The toy electrical traffic signal as defined in claim 3, wherein said transparent strips are clamped and held in position between the edges of said partitions and the inner surfaces of the corresponding walls of the housing.

6. A toy electrical signal comprising a compartment having front, rear and oppositely disposed side walls, said side walls having colored transparencies of the same color and said front wall having a transparency of another color, and 10 an electric lamp in said compartment.

7. A toy electrical signal comprising a housing having upper intermediate and lower compartments each having front, rear and oppositely disposed side walls, each compartment having a 15 colored transparency in each side and front wall, the transparencies of the side walls of the lower compartment being of the same color but different from that of the side wall transparencies of the upper compartment, the transparencies of 20

the front walls of the upper and lower compartments being of colors different from each other and from the colors of the side wall transparencies of the corresponding compartments, and all of the transparencies of the intermediate compartment being the same color but different from the colors of the transparencies of the other compartments, and an electric lamp in each compartment.
